UNITED STATES PATENT OFFICE

2,419,016

LUBRICATING OIL CELL

Reid B. Gray, Dundalk, and Joseph C. De Weese,
Essex, Md., assignors to The Glenn L. Martin
Company, Middle River, Md., a corporation of
Maryland

Application March 19, 1942, Serial No. 435,414

2 Claims. (Cl. 154—43.5)

1

This invention relates to a storage reservoir or cell having a laminated flexible wall structure for holding oil, and particularly hot lubricating oil. In use, the invention has particular application to the lubricating systems of internal combustion engines in aircraft, tanks, boats and other vehicles.

An object of the invention is to prepare a flexible, substantially non-elastic cell or bag composed of a plurality of laminated sheets of material secured together, the several sheets possessing physical and chemical characteristics that impart to the completed structure the desired qualities for retaining hot oil.

The bag or cell constructed of the present novel laminated sheet may be used as the interior of a rigid walled tank, or may be placed within a frame or holder of the type disclosed in Gray and Zivi, Patent 2,102,590. In this prior patent there is disclosed the broad idea of mounting a flexible walled inner container within a rigid outer container and wherein the normal volumetric capacity or exterior dimensions of the inner flexible container are slightly larger than the normal volumetric capacity or interior dimensions of the exterior container, whereby the inner container is under some degree of compression and there is no likelihood of friction or wear thereof against the outer container.

In the accompanying drawings:

Fig. 1 is a diagrammatic view of an inner flexible cell or bag 1, made in accordance with the following specification, supported within an exterior rigid tank or frame 10.

Fig. 2 is an enlarged cross-section through the improved cell wall.

Specifically, the hot oil reservoir is made of any desired size or configuration and consists of a flexible, substantially non-elastic bag composed of a plurality of pliable, non-stretchable sheets cemented together with the innermost sheet, in contact with the hot oil, composed of a resistant thermo-setting plastic material. In Figure 2 there is disclosed a cross-section through this hot oil resistant cell in which numeral 3 denotes an inner hot oil resistant layer of a thermo-setting plastic material, such as neoprene, a rubber substitute prepared from a chloroprene, capable of withstanding temperatures of approximately 225° F. The layer 5 behind the heat resistant layer 3 is preferably composed of a high molecular weight iso-butene polymer obtainable in the open market under the trade name, "Vistanex." As an alternative, the layer 5 may be a compound

2

of fifty per cent Vistanex and fifty per cent natural rubber.

Exterior of the layer 5 is a soft vulcanized rubber layer 7, to which is secured an outer layer 9, composed of high strength cotton fabric or a glass fabric. This latter layer is resistant to abrasion and prevents elongation of the cell per se. It will be understood that the several layers are cemented or otherwise secured together to form a unitary laminated structure.

This particular form of non-elastic, laminated cell has been found peculiarly well adapted for retaining hot lubricating oil when constructed in the form of an inner cell mounted in an exterior tank or holder of slightly smaller dimensions than the flexible cell.

Although the thickness of the several layers 3, 5, 7 and 9 may vary and are not strictly critical, a practical form of cell has been constructed wherein the inner oil resistant layer is .0025 in thickness, the synthetic or compound layer 5 is .004 in thickness, the soft vulcanized rubber layer 7 is .094 in thickness and the exterior high strength resistant cotton or glass fabric layer 9 is .007 in thickness.

What we claim is:

1. A self-sealing hydrocarbon liquid storage container comprising a metal frame, a flexible cell within said frame, the outer dimensions of the cell being proportioned with respect to the inner dimensions of the frame so that the hydrostatic load of the liquid is transmitted to said frame, the cell walls being unstressed by the liquid load, the walls of said cell being free of the frame and including at least four layers arranged

35 in the sequence named; a layer of synthetic plastic material resistant to the chemical action of the hydrocarbon liquid to be held in said tank, a layer comprising substantially a high molecular weight iso-butene polymer subject to swelling upon contact with the hydrocarbon liquid, a soft vulcanized protective layer, and an outer fabric layer, all of said layers being adhesively secured to adjacent layers to form a laminar structure.

45 2. A self-sealing hydrocarbon liquid storage container comprising a metal frame, a flexible cell within said frame, the outer dimensions of the cell being proportioned with respect to the inner dimensions of the frame so that the hydrostatic load of the liquid is transmitted to said frame, the cell walls being unstressed by the liquid load, the walls of said cell being free of the frame and including at least four layers arranged in the sequence named; a layer of synthetic plastic material resistant to the chemical

action of the hydrocarbon liquid to be held in said tank, a layer comprising substantially 50% of high molecular weight iso-butene polymer and 50% natural rubber subject to swelling upon contact with the hydrocarbon liquid, a soft vulcanized protective layer, and an outer fabric layer, all of said layers being adhesively secured to adjacent layers to form a laminar structure.
